(57) CLAIM

The ornamental design for an accessory holder, as shown and described.

DESCRIPTION

FIG. 1 is an isometric view of an ornamental design for an accessory holder;

FIG. 2 is a front elevation view thereof, the rear elevation view being a mirror image thereof;

FIG. 3 is a right side elevation view thereof, the left side elevation view being a mirror image thereof;

FIG. 4 is a top plan view thereof;

FIG. 5 is a bottom view thereof; and,

FIG. 6 is a top plan view thereof, showing a timepiece securely accommodated and held within the accessory holder.

The broken line showing of the timepiece in FIG. 6 is for the purpose of illustrating environment and forms no part of the claimed design.

1 Claim, 4 Drawing Sheets
